UNITED STATES PATENT OFFICE.

MICHAEL F. BROGAN, OF LAWRENCE, MASSACHUSETTS, ASSIGNOR TO UNITED SHOE MACHINERY COMPANY, OF PATERSON, NEW JERSEY, A CORPORATION OF NEW JERSEY.

LASTING-BUTTONER.

1,187,885.

Specification of Letters Patent. Patented June 20, 1916.

Application filed July 8, 1915. Serial No. 38,793.

To all whom it may concern:

Be it known that I, MICHAEL F. BROGAN, a citizen of the United States, residing at Lawrence, in the county of Essex and State 5 of Massachusetts, have invented certain Improvements in Lasting-Buttoners, of which the following description, in connection with the accompanying drawings, is a specification, like reference characters on the 10 drawings indicating like parts in the several figures.

This invention relates to devices for securing and holding the flaps of button shoes during the process of manufacture of the 15 shoe and particularly during the lasting process, which requires that the upper of the shoe be properly fitted over the last. It has been the practice to close the upper previous to lasting by means of several of 20 the buttons, and when the lasts were drawn, the upper was unbuttoned by a pull on the fly, this operation frequently resulting in pulling buttons from the upper and in breaking or distorting the buttonholes.

25 The present invention is concerned with the type of buttoner comprising a plurality of spaced and connected fasteners for a plurality of buttons and buttonholes, such as shown in Letters Patent of the United 30 States, No. 967,939, of Aug. 23, 1910 to Krippendorf, and is designed to provide a buttoner of improved construction, which has a wide range of use and is simple in construction and easy of application and removal.

35 For the purposes of description, the device of this invention is termed in the specification and claims a "lasting buttoner", but the use of the word "lasting" is in no sense 40 a limitation as to use and application, for it will be obvious that a buttoner of the character described may be used at other times.

45 One feature of the invention consists in a buttoner of such structure that it may be readily formed as an integral article from a single piece or length of material, such as wire.

50 Another feature of the invention consists in yielding connections between the fasteners to permit varying separation.

55 A further feature consists in a curvilinear arrangement of button and buttonhole grips corresponding substantially with the curvilinear arrangement of the buttons and

buttonholes of a shoe upper so that the button and buttonhole flaps will be held by the buttoner in the position they assume when the parts are actually buttoned.

A further feature of improvement resides 60 in a certain novel construction permitting the ready application and removal of the device.

These and other features of improvement will be more fully apparent from the detailed specification following, taken in connection with the accompanying drawings forming part of this specification and illustrating one type of buttoner embodying the 65 invention.

In the accompanying drawings: Figure 1 70 illustrates in perspective the application of one form of my invention to the buttons of a shoe upper, the buttonhole flap being unfastened; Fig. 2 shows the buttoner applied 75 to the shoe upper with the shoe positioned for lasting, the lines of lasting pull on the upper being indicated by arrows, Fig. 3 is a transverse section through the upper with the buttoner applied thereto, and Fig. 4 80 illustrates slightly modified forms of the invention.

In the drawings, 2 designates the button flap and 4 the buttonhole flap of a conventional form of button shoe.

85 The buttoner embodying the present invention, as illustrated herein, comprises a series of what may be termed "fasteners" spaced and connected, these fasteners comprising button and buttonhole engaging 90 means which may be termed generically, "grips". I have provided such a structure of a very simple character and of a construction permitting the formation of the entire buttoner from a single length or piece 95 of material, such as a single length of wire. This wire may be bent by a machine or otherwise to provide a series of spaced wire clasps or grips for the buttons with adjacent and integral projecting portions or 100 grips for the buttonholes, each pair of grips or "fastener" being integrally connected with the adjacent fastener, this connection comprising a length of wire which is flexible, so that the space between the fasteners 105 may be varied.

The illustrative buttoner shown in Figs. 1, 2 and 3 of the drawings is formed by taking a length of wire and bending each end to form a loop or clasp 6, the outer end 110

of the loop being closed by upwardly extending arms, the ends of which are bent to form hooks 8, extending in a direction inwardly of the edge of the buttonhole flap 5 and transversely of the buttonhole. In the form shown in Fig. 1, these hooked portions 8 extend at an angle toward each other and toward the intermediate fastener. The hooked portions 8 are intended to overlie the 10 upper adjacent the buttonholes with contact faces 10 adjacent to the bend of the hooks arranged to engage the edge of the buttonhole and limit the relative movement between the button and buttonhole flaps to a 15 position where the buttonholes will be properly positioned relative to the buttons.

The terminal fasteners are connected to an intermediate fastener or fasteners by bending the rear inner ends of the loops 6 20 at an angle to form connecting arms 12 which, in turn, as shown in Fig. 1, are bent outwardly to form a button clasp or grip 14, the outer end of the clasp being closed by bringing the opposite sides of the wire 25 together and projecting the wire upwardly and bending the end outwardly, as at 16, to provide an intermediate buttonhole grip, the wire at the angle of the bend, as at 18, engaging the edge of the buttonhole to 30 limit the separation of the buttonhole and buttonhole flaps at this point. The connecting arms 12 of the fastener are resilient to permit varying separation of the fasteners so as to accommodate them to different 35 spacings of buttons and buttonholes within a reasonable range. The wire clasps or grips for the buttons are preferably made sufficiently large to inclose loosely the eye of the button and permit accommodation to 40 varied and, when necessary, unequal spacing of the buttons. It will be noted that the inner ends of the wire clasps are bent toward each other to provide a narrow or 45 restricted opening, through which the eye of the button slides when the clasp is applied to the button flap.

To provide for the curvilinear arrangement of the buttons and buttonholes of a 50 shoe upper the contact surfaces 10 and 18 of the buttonhole grips are relatively offset to lie in the line of such a curvilinear arrangement. The engaging surface 18 will, therefore, project out beyond the engaging surfaces 10 of the terminal buttonhole grips, so that these points will represent the points in a curved line of buttonholes which should 55 be engaged by the buttonhole grips when the buttonhole flap is properly positioned relatively to the button flap. The buttons 60 will engage the upwardly extending arms of the buttonhole grips with the buttonhole engaging surfaces of the grips positioned substantially centrally above the buttons. The button eyes will be positioned, therefore, substantially in line with the outer ends of

the buttonholes and the button and button-hole flaps will be held in the positions they should occupy when the flaps are actually buttoned and the upper held tightly to the last. This coöperation of the buttonhole 70 grips, button clasps and buttons provides the button clasps with relatively offset button holding positions corresponding with the offset positions of the buttonhole grips.

The illustrative buttoner, shown in Fig. 1, 75 is applied to the shoe by sliding the inner edge of the buttoner toward a line of buttons on the button flap, so as to insert the eyes of these buttons through the necks or restricted portions of the clasps 6 and 14 80 to bring them adjacent or against the outer ends of the clasps. The lower of the aligned buttonhole is then buttoned over the lower hook 8 of the series of fasteners, this hook extending transversely of the buttonhole 85 and upwardly of the flap, as will be evident from Fig. 2. The next two buttonholes are then inserted over the next adjacent hooks in an obvious manner.

It will be noted that the intermediate 90 hook 16 extends in line with its buttonhole and that the upper hook 8 extends transversely of the buttonhole and downwardly from the buttonhole flap. When thus applied, it will be evident that the lasting 95 strain upon the shoe upper is in a direction transversely of the upper and also longitudinally. The buttonhole engaging surfaces 10 and 18 will serve to limit the transverse relative movement of the button and buttonhole flaps caused by the lasting strain and will position the buttonholes in line with the button eyes. The lower hook 8 will prevent the upper from being drawn downwardly and over the upper hook 8 and 100 the intermediate hooked portion 16. The upper hooked portion 8, which extends downwardly is of substantial assistance in facilitating the removal of the buttoner from the shoe. This removal is accomplished by moving the buttonhole flap downwardly over the upper hook 8 to clear the hook and then by grasping the buttoner and moving it transversely of the button flap, and at the same time turning the two 105 lower hooked ends 16 and 8 inwardly, so that the hooks clear their buttonholes and the entire buttoner is drawn from beneath the buttonhole flaps, the buttons being easily drawn through the restricted ends of their 110 clasps.

By providing terminal fasteners of the 115 series of fasteners with hooked portions extending transversely of their buttonholes and toward each other and the intermediate fastener or fasteners of the series, the buttoner is made reversible so as to be adapted to both right and left shoes. In the form 120 illustrated in Figs. 1 to 3, only three fasteners have been shown, but it will be under- 125 130

stood that the specific number shown is not intended as a restriction but merely as an illustration.

While it is preferable to form the terminal buttonhole grips of the series of fasteners with oppositely bent ends to make the buttoner adapted for both right and left shoes, it will be obvious that the buttoners may be made for either right or left shoes and any number of fasteners. In Fig. 4 of the drawings, I have illustrated such an arrangement. The length of wire is bent in the manner heretofore described to form a series of spaced button clasps 20, having at their outer ends a series of buttonhole engaging hooks or grips 22. For right shoes one end hook of the series will be bent to extend transversely of its buttonhole, as at 24, Fig. 4, and for left shoes, the opposite end of the series will be bent in the opposite direction, as at 26. In the form shown in Fig. 4, the buttonhole grips, other than the one terminal grip 24 or 26, extend in the line of their buttonholes similarly to the hooked end 16 of the intermediate fastener of Fig. 1 of the drawings.

Having thus described my invention, what I claim as new and desire to secure by Letters Patent of the United States is:

1. A lasting buttoner for holding the flaps of button shoes, comprising a plurality of integrally connected fasteners, each fastener comprising a button engaging wire loop having its end bent to form a hook to engage the buttonhole.

2. A lasting buttoner for holding the flaps of button shoes, comprising a plurality of integral spaced fasteners, each fastener comprising a button engaging wire loop, bent upwardly and toward the edge of the flap to provide a hook for engaging the buttonhole.

3. A lasting buttoner for holding the flaps of button shoes, comprising a plurality of integral spaced fasteners, each fastener comprising a button engaging wire loop having its sides adjacent to one end of the loop disposed in substantial engagement and bent upwardly to form a double hook for engaging the buttonhole.

4. A lasting buttoner for holding the flaps of button shoes, comprising a plurality of spaced fasteners integrally connected and each comprising a button grip and a button-hole grip, said plurality of fasteners and connections being formed from a single piece of metal.

5. A lasting buttoner for holding the flaps of button shoes, comprising a single length of wire or the like, bent to form a plurality of spaced integrally connected fasteners, each fastener including a button clasp and an adjacent upwardly projecting portion arranged to extend through a button hole.

6. A lasting buttoner for holding the flaps of button shoes, comprising a single length

of wire or the like, bent to form a plurality of spaced integrally connected fasteners, each fastener including a button grip and a buttonhole grip, the wire connections between adjacent fasteners being yielding to permit varying separation.

7. A lasting buttoner for holding the flaps of button shoes, comprising a plurality of spaced and integrally connected fasteners, each fastener comprising a button grip and an adjacent buttonhole grip, said grips being relatively offset to provide a curvilinear arrangement of button and buttonhole grips corresponding substantially with the curvilinear arrangement of the buttons and buttonholes of a shoe upper.

8. A lasting buttoner for holding the flaps of button shoes, comprising a plurality of spaced and integrally connected fasteners, each fastener comprising a button clasp and an adjacent and upwardly projecting hook arranged to extend through a buttonhole and engage the edge of the upper, said button clasps and the upper engaging portions of the hooks being relatively offset to provide a curvilinear arrangement of button clasps and upper engaging hooks corresponding substantially with the curvilinear arrangement of the buttons and buttonholes of a shoe upper.

9. A lasting buttoner for holding the flaps of button shoes, comprising a series of spaced and connected fasteners, each fastener comprising a button grip and a projecting portion arranged to extend through a buttonhole and engage the upper, one terminal projecting portion of the series of fasteners having its end arranged at an angle to extend transversely of and beyond its buttonhole.

10. A lasting buttoner for holding the flaps of button shoes, comprising a plurality of spaced and connected fasteners, each fastener comprising a button grip and an adjacent projecting hook arranged to extend through the adjacent buttonhole, at least one of the hooks of the plurality of fasteners having its end turned inwardly of the button flap edge and transversely of its buttonhole.

11. A lasting buttoner for holding the flaps of button shoes, comprising a series of spaced and integrally connected wire fasteners, each fastener comprising a button clasp and an adjacent integral hook arranged to extend through the adjacent buttonhole and engage the edge of the upper, the terminal button clasps of the series and the upper engaging portions of the terminal hooks of the series being laterally offset relatively to the corresponding parts of the intermediate fasteners or fastener to provide a curvilinear arrangement of button clasps and buttonhole hooks corresponding substantially with the curvilinear arrangement

of the buttons and buttonholes of a shoe upper.

12. A lasting buttoner for holding the flaps of button shoes, comprising a series of at least three spaced and connected fasteners, each fastener comprising a button grip and an adjacent projecting hook arranged to extend through the adjacent buttonhole, the terminal hooks of the series of fasteners being turned inwardly of the button flap edge and toward the intermediate fastener or fasteners.

Copies of this patent may be obtained for five cents each, by addressing the "Commissioner of Patents, Washington, D. C."

13. A lasting buttoner for holding the flaps of button shoes, comprising a plurality of integrally connected and spaced fasteners, each fastener comprising a button engaging wire loop to inclose loosely a button eye, said loop having its end bent upwardly to form a hook for engaging a buttonhole, said fasteners having resilient wire connections permitting varying separation. 15 20

In testimony whereof I have signed my name to this specification.

MICHAEL F. BROGAN.
